UNITED STATES PATENT OFFICE.

GEORGE F. McCHEY, OF PROVIDENCE, RHODE ISLAND.

BRAIDING MACHINE.

Application filed October 27, 1925. Serial No. 65,197.

This invention relates to an improved construction of braiding machines of the class provided with oscillating carriers; and has for its object to provide in such a machine two cooperating spaced raceway plates having raceways of different contours, the carriers being mounted in the raceways of both plates and driven by gears mounted below both of said raceway plates. 5 A further object of this invention is to provide carriers of the oscillating type having portions guided in both of the raceways and also having an extended portion guided between these raceway plates so as to support that portion of the carrier above the plates in an upright position. 10

With these and other objects in view, the invention consists of certain novel features of construction, as will be more fully described, and particularly pointed out in the appended claims.

In the accompanying drawings:

Figure 1 is a top view of this improved braiding machine, showing portions of the two upper raceway plates as broken away to expose the driving gear and also the supporting plate below. 25

Figure 2 is a sectional side elevation showing a portion of my improved braiding machine and illustrating the two upper raceway plates as spaced apart and showing the carrier as guided in the raceways of both plates and driven by gears mounted below both plates. 30

Figure 3 is a side elevation of a portion of my improved carrier showing the same partly in section.

Figure 4 is a view of the foot portion of my improved carrier. 40

Figure 5 is a top view of my guide member showing the same as split and adapted to be bent and the parts separated to engage the neck of the carrier.

Figure 6 is a side elevation of the guide illustrated in Figure 5. 45

Figure 7 is a perspective view of the shoe member which is guided in the lower raceway of my improved braiding machine.

Figure 8 is a modification showing the two plates as spaced so as to provide a guide at the foot of the carrier. 50

Figure 9 is a modification showing a top view of a part of a single raceway plate in which both of the raceways are formed. 55

Figure 10 is a sectional elevation on line 9-8 of Figure 9.

Figure 11 is a sectional view of the under side of the carrier on line 11-11 of Figure 10.

It is found in practice in the operation of 60 braiding machines in order to obtain a high degree of speed, of advantage to reduce the extent of oscillation or in and out motions of the carriers relative to the braiding center, which style of machine has the advantage of reducing the travel of the yarn tension weight and thereby reduce the friction on the yarn, which weight travel tends to remove the lustre, particularly on yarns having glossy or finished surfaces such as 65 artificial silks and the like commonly known as "Rayon"; and to obviate this detrimental effect, I have provided a machine of simple and practical construction that has two cooperating narrowly-spaced plates 70 having raceways of different contours, in both of which raceways parts of the carrier are caused to run, the neck portion of the carrier engaging the upper raceway while the shoe portion thereof is arranged to extend down through the lower raceway plate to be engaged and operated by the usual 75 train of carrier driving gears which, in this case, are located below both of the raceway plates. By this construction, I am enabled 80 to readily convert the ordinary braiding machine having a single raceway plate with the old type of carrier, into a braiding machine of the oscillating carrier type, by 85 simply mounting an upper raceway plate 90 having raceways of less in and out contours, whereby the oscillating carrier may be readily mounted to operate between these two raceway plates to produce the desired oscillating effect; and the following is a detailed 95 description of the present embodiment of my invention and showing one means by which these advantageous results may be accomplished:

With reference to the drawings, 10 designates the upper raceway plate in which is formed the raceways 11 being relatively slightly offset from either side of a central line through them to reduce the oscillating action of the upper portion of the carrier. 100

Spaced from this upper plate is the lower raceway plate 12 which is held in set spaced relation by the spacer washers 13 through which the bolts 14 pass. This plate is provided with raceways 15 which have a more pronounced contour than those of the upper raceway plate. 110

Spaced from this lower raceway plate is the base plate 16 which is held in spaced relation by the spacers 17 and secured by the bolts 14. Supported on this lower plate 16 on the central studs 18 is a train of carrier driving horn gears 19 each of which is provided with arms or horns 20 to engage and drive the carriers 21.

These carriers are provided with the usual package carrying spindle 22 and weight guide 23 also with a guide neck portion 24 having a guide member 25 loosely mounted thereon, which guide member is preferably formed of steel and is split as at 26 whereby it is adapted to be opened or sprung apart sufficiently to receive the neck portion 24 in its bore 26 and then closed together to be loosely mounted on the neck and so provide a suitable guide for this portion of the carrier in the upper raceway.

In order to support this carrier against a lateral tipping motion, I have formed a broad or extended foot member 27 which extends along in the space between the upper 28 and lower raceway plate. This circular flange is also adapted to extend into an opening 32 in the guide foot 27 of the carrier to loosely engage the same, whereby the foot is pivotally connected to the shoe member to be operated thereby without cramping.

By my improved construction of braiding machines, when it is desired, the usual or old style machine which comprises the lower or base plate 16 on which the horn gears are mounted and the lower raceway plate 12, may be readily converted into a braiding machine of the oscillating carrier type, by mounting the upper raceway plate 10 thereon having raceways of the desired contours and mounting the same in narrow-spaced relation above the raceway plate 12 and then by providing a set of carriers of the type above described this machine may be operated as a braiding machine of the oscillating type.

In some instances, instead of providing a broad flat guide foot 77 which is guided between the plates 10 and 12, I may space the plates wider apart and guide the foot 39 on the pin 40 of the shoe 41, as illustrated in Figure 8.

I do not wish to be limited to the use of two separate raceway plates, as a single raceway plate 33 having two raceways including the inner groove 34 and the slot 35 both formed therein, as illustrated in Figures 9 and 10, may be employed, if desired, which arrangement of parts will produce the desired oscillating effect in the carrier 36 which has a guide finger 37 running in the inner groove 34 and a guide shank 38 extending through the slot 35, the latter to be engaged and operated by a horn gear or other driving mechanism, not shown.

My improved braiding machine is very simple and practical in construction and is effective in its operation.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a braiding machine, two cooperating raceways having portions disposed out of vertical alignment with each other, a carrier having offset portions and guided in both of said raceways, and means located below the raceways for driving said carrier therethrough to impart to the carrier an oscillating motion.

2. In a braiding machine, two cooperating spaced raceway plates having portions disposed out of vertical alignment with each other, a carrier having offset portions and guided in the raceways of both plates, and means located below both of said raceway plates for driving said carrier and causing its said offset portions to oscillate relatively in said raceways.

3. In a braiding machine, two cooperating raceway plates having raceways of different contours, said plates being in spaced relation, a carrier of the oscillating type having offset portions guided in said different raceways, and a train of carrier driving gears operatively mounted below both of said plates.

4. In a braiding machine, two cooperating spaced raceway plates having raceways of different contours, a carrier having relatively offset portions guided in said raceways producing an oscillating motion of said portions when driven through said raceways, and driving gears for said carriers operatively mounted below both of said plates.

5. In a braiding machine two cooperating spaced raceway plates having raceways of different contours, a carrier having relatively offset portions guided in both of said different raceways, a broad guide foot mounted to slide and be guided in the space between said plates to assist in supporting the carrier in an upright position, and a train of carrier driving gears operatively mounted below both of said plates.

6. In a braiding machine, two narrowly-spaced raceway plates having raceways of different contours, a carrier having a shank portion guided in the upper raceway and a shoe member guided in the lower raceway, said carrier having a guide foot pivoted to said shoe, and driving gears mounted below said lower plate for driving said carrier through said shoe.

7. In a braiding machine, two cooperating spaced raceway plates having raceways of

different contours, a carrier of the oscillating type having portions guided in both raceways and having a foot portion with an extended guiding surface mounted to slide between said plates to support that portion of the carrier above both plates in an upright position, and carrier driving gears operatively mounted below said raceway plates.

8. In a braiding machine, two cooperating narrowly spaced raceway plates having raceways of different contours, a carrier having a shank portion guided in the upper raceway, a shoe member guided in the lower raceway, said carrier having a broad extended guide foot guided between said plates and pivotally connected to said shoe, a lower third plate, a train of carrier driving gears

supported on said lower plate beneath both of said raceway plates.

9. In a braiding machine, two cooperating narrowly spaced raceway plates having raceways of different contours, a carrier having a shank portion, a swiveling guide member on said shank guided in the upper raceway, a shoe member guided in the lower raceway, 20 said carrier having a broad extended guide plate guided between said raceway plates and pivotally connected to said shoe, a lower third plate, a train of carrier driving gears supported on said lower plate beneath both 25 of said raceway plates.

In testimony whereof I affix my signature.

GEORGE F. McCABEY.
